(57) CLAIM

The ornamental design for a bath fizzer, as shown and described.

DESCRIPTION

FIG. 1 is a top perspective view of a bath fizzer.

FIG. 2 is a top view of the bath fizzer.

FIG. 3 is a first side view of the bath fizzer.

FIG. 4 is a second side view of the bath fizzer.

FIG. 5 is a bottom view of the bath fizzer.

FIG. 6 is a first bottom perspective view of the bath fizzer; and,

FIG. 7 is a second bottom perspective view of the bath fizzer. The broken lines of FIGS. 1-7 illustrate portions of the bath fizzer that form no part of the claimed design.
